UNITED STATES PATENT OFFICE.

MARINUS HVID, OF CHICAGO, ILLINOIS.

OPEN-HEARTH FURNACE.

1,296,189.

Specification of Letters Patent.

Patented Mar. 4, 1919.

Application filed October 21, 1918. Serial No. 259,013.

To all whom it may concern:

Be it known that I, MARINUS HVID, a citizen of the United States, residing at Chicago, in the county of Cook and State of Illinois, have invented a new and useful Improvement in Open-Hearth Furnaces, of which the following is a specification.

My invention relates to improvements in open-hearth furnaces wherein the gases 10 are directed from slag-pockets to the tops of checker-chambers through flues leading from the former to the latter, to cause the hot dust-laden gases to pass downwardly through the checkers into flues beneath 15 them, from which flues, thus provided at the bottoms of the checkers, the spent gases pass through flues leading to the stack and provided with reversing valves, and sometimes, to utilize the residual heat of the gases, through 20 boilers on their way to the stack.

The heavy matter carried by the hot gases, and which is termed "dust" in the art, tends to clog the checkers, thereby reducing their 25 capacity, and this result is increased where the fuel used is tar—a product of coke-manufacture or a residue of petroleum distillation,—the dust from which is of adhesive quality. It is the practice to fill the checker-chambers only partially with checker-work 30 to leave sufficient space in the chambers over the checkers to enable men to enter, from time to time, and work in these spaces to dislodge the dust by poking it down through the interstices to clear them. 35 The provision of such spaces further reduces the capacity and therefore the efficiency of the checker-chambers.

Moreover, where, as heretofore in such open-hearth furnaces, the spent gases from 40 the checkers discharge to the stack through flues at the base of the checker-chambers, access to the latter, as for tearing down and rebuilding, is obstructed by complicated reversing-valve mechanism and flues, which 45 rise above the ground-surface at such base, whereby the work of repairing the checkers is impeded and greatly augmented.

It is the object of my invention to overcome these and other conditions; and this I 50 accomplish by my improvements hereinafter described and which are illustrated in a preferred embodiment and in their co-operative relation in the accompanying drawings, in which:—

55 Figure 1 is a broken transverse section of an open-hearth regenerative furnace, on line

1—1, Fig. 2; Fig. 2 is a section on line 2—2, Fig. 1; Fig. 3 is a section on line 3—3, Fig. 2, Fig. 4 is a plan view partly in section on line 4—4, Fig. 1 or Fig. 2, and Fig. 5 is a horizontal sectional view of the checker-work on line 5—5 of Fig. 1.

The structure, as a whole, is like an ordinary and well-known type of one-hearth regenerative furnace and need not, therefore, 65 be herein described in more detail than may be required to afford a clear understanding of the features of my improvement and explain their functions.

From the lower part of each slag-pocket 70 5 below the hearth 6, the hot-gas flue 7 leads directly in downward inclination to a dust-chamber 8 underneath the checker-chamber 9, from the upper end of the outer side of which the exhaust-flue 10 leads to the gas-inlet conduit 11 (Fig. 4), which is common 75 to the various flues beyond the checkers and is equipped with valves 12 for the usual reversing purpose; and from this conduit extend the waste-heat boiler-flue 13 and the 80 stack-flue 14, each equipped with a shut-off valve 15.

As shown in Fig. 1, the checker-work entirely fills the chamber 9, except a portion thereof at 16 and for a mere pocket 17 provided at the inlet-end of the flue 10. The space 16 affords a relatively shallow section 85 of the checkers, for the purpose hereinafter explained.

The hot gases passing from the hearth 6 90 through a slag-pocket 5 flow through the respective flue 7 into the chamber 8, and the larger portion of the dust carried by them precipitates in the chamber 8. Thus the gases which rise through the checker-work, being relieved of such portion of the dust, are prevented from depositing it in the checkers, thereby largely avoiding the clogging effect referred to, with the advantage of augmenting the efficiency of the checker-chambers; and their efficiency is further enhanced, by omitting the space over their upper portions, since the deposits of dust 95 in the interstices is comparatively so little as to render unnecessary provision of such space for men to enter it for poking the checkers to clear them, as hereinbefore referred to.

The shallower section at the end of the checkers adjacent the slag-pocket structure 110 affords a path of lesser resistance to the hot gases and induces them, on entering the

dust-chamber 8 from a flue 7, to rise vertically in that section and pass thence through the entire checker-work to the pocket 17 and escape from the latter to the flue 10. If the checker-work were to entirely fill the chamber 9, the stack-draft would tend to pull the gases diagonally from the mouth of the flue 7 through the checkers to the pocket 17 and flue 10, thereby slight- 10 ing the heating of their inner portion. By providing this shallower section, the heat of the gases is distributed more uniformly throughout the checker-chamber.

The accumulations of dust in the chamber 8 may be removed, from time to time, through openings, one of which is represented at 18 in Fig. 1, for convenient access to which a runway is shown to be provided at 19 for loading the dust and carting it away.

As will be seen, by directing the hot gases from the slag-pockets downwardly into the dust-intercepting chamber underneath the checkers, the flues 10 and connections therewith through which they discharge to the stack, may all be in elevated position, where they are out of the way of obstructing access to the chamber 8 and to the checkers when required, as for tearing down and rebuild- 30 ing them.

I claim:

1. In an open-hearth furnace having a slag-pocket below the hearth, a checker-chamber communicating with the stack, and a dust-chamber underneath the checkers, a waste-gas flue leading directly in downward unobstructed inclination from the lower part of the slag-pocket into the dust-chamber.
2. In an open-hearth furnace having a slag-pocket below the hearth, and a checker-

chamber communicating with the stack and a dust-chamber underneath the checkers, a waste-gas flue leading directly in downward inclination from the lower part of the slag-pocket into the dust-chamber, the checker-work approximately filling the checker-chamber and forming a shallow section over the gas-admission side of the dust-chamber.

3. In an open-hearth furnace having a slag-pocket below the hearth, a checker-chamber and a dust-chamber underneath the checkers, an unobstructed waste-gas flue leading directly from the lower part of the slag-pocket into the dust-chamber, and an exhaust-flue leading from the upper part of the checker-chamber.

4. In an open-hearth furnace having a slag-pocket below the hearth, a checker-chamber and a dust-chamber underneath the checkers, a waste-gas flue leading directly from the lower part of the slag-pocket into the dust-chamber, and an exhaust-flue leading from the upper part of the checker-chamber.

5. In an open-hearth furnace having a slag-pocket below the hearth, a checker-chamber and a dust-chamber underneath the checkers, a waste-gas flue leading directly in downward inclination from the lower part of the slag-pocket into the dust-chamber, and an exhaust-flue leading from the upper part of the checker-chamber, the checker-work approximately filling the checker-chamber and forming a shallow section over the gas-admission side of the dust-chamber, and a pocket adjacent the inlet end of the exhaust-flue.

MARINUS HVID.
